APPARATUS FOR MAKING ABRASIVE ARTICLES

Edward Van der Pyl, Holden, Mass., assignor to
 Norton Company, Worcester, Mass., a corpora-
 tion of Massachusetts

Application July 23, 1942, Serial No. 452,009

3 Claims. (Cl. 204—263)

This invention relates to a method of and apparatus for making abrasive articles and with regard to its more specific features to the fixing of diamond abrasive grains, preferably in a single layer, on a suitable backing.

An object of the invention is to provide a simple, practical and efficient method and apparatus for the manufacture of abrasive articles.

Another object is to provide for the dependable attachment or mounting of abrasive particles to a metallic or other conductive support without the use of an organic or other cement, in a manner to meet reliably the requirements of practical use.

Another object is to provide a practical and simple apparatus and method for making diamond abrasive articles with the abrasive grains in single-layer form.

Another object is to produce diamond abrasive articles, particularly articles capable of embodiment in various shapes, such as tapered or frusto-conical, in an inexpensive practical way.

Another object of the invention is to provide a practical, easily operated, and inexpensive means for mutually positioning and holding together an article and abrasive grains which are to be assembled to form the abrasive article.

Another object of the invention is to provide a dependable means to effect close and even dispersion or distribution of the abrasive granules relative to the selected backing or support.

Other objects will be in part obvious or in part pointed out hereafter.

The invention accordingly consists in the features of construction, combinations of elements, arrangements of parts and in the several steps and relation and order of each of said steps to one or more of the others thereof, all as will be pointed out in the following description, and the scope of the application of which will be indicated in the following claims.

In the accompanying drawing illustrating one of various possible embodiments of the mechanical features of the invention,

Figure 1 is a top plan view of apparatus for carrying out my invention;

Figure 2 is a cross sectional view on an enlarged scale as seen along the line 2—2 of Figure 1, certain parts being shown in front elevation;

Figure 3 is a detached vertical sectional view on an enlarged scale as it is seen along the line 2—2 of Figure 1 showing the details of construction and assembly of a mount for a backing or support and a container for the abrasive grains;

Figure 4 is a horizontal sectional view taken on the line 4—4 of Figure 3;

Figure 5 is a detached vertical sectional view of a device or collet for releasably engaging and holding assembled the support and abrasive grain container;

Figure 6 is a side elevation, partly in section, of funnel means for supplying abrasive grains to the container;

10 Figure 7 is an end view of the funnel as seen from the right in Figure 6;

Figure 8 is a side elevation of the finished abrasive article, illustrated in the form of a dental point having a frusto-conical operative portion supporting the abrasive grains; and

15 Figure 9 is a fragmentary central cross section on a greatly enlarged scale of the operative portion of the dental point of Figure 8, to show better the relation between the support and the 20 abrasive grains.

Similar reference characters refer to similar parts throughout the several views.

Let it be assumed for purposes of illustration that the abrasive article to be made is a so-called 25 dental point; it comprises a metal shank 10 and a portion 11 that is to be covered with abrasive grains. Such an illustrative backing, or support for abrasive grains, I mount in any suitable

30 dental point; it comprises a metal shank 10 and a portion 11 that is to be covered with abrasive grains. Such an illustrative backing, or support for abrasive grains, I mount in any suitable support 12 and arrange to relate with porous means 13, formed of material, such, for example, as porous refractory material, pervious to an electro-plating solution in which the porous means is positioned as will be explained, and spaced from the backing 11 to receive abrasive

35 grains 60 between it and the backing 11. The means 13 serves as retaining means holding the backing 11 and the mass of abrasive grains 60 in mutual contact while plating metal is being deposited upon the backing 11, thereby building

40 up a metal matrix encompassing the abrasive grains positioned against or adjacent to the surface of the backing. The form of the porous retaining means 13 and the means for supporting the blank to be coated with abrasive grains may,

45 of course, be widely varied in accordance with the requirements of the particular backing to which the abrasive grain is to be fixed. In the specific illustration given herein, the means for supporting a dental point blank consists of a holder 12 at the lower end of a shaft 14 extending

50 through and supported from, as by screw threads 15, an inverted cup-shaped support member 16, said shaft 14 being counter-bored at its lower end at 17 to receive the rear end or

55 shank 10 of said dental point blank. The annu-

lar wall 17a of the counter-bored lower end of shaft 14 is preferably divided into a number of spring fingers 18, which may be formed by slotting the wall at spaced intervals, as by slots 19, thus forming a collet-like holder to receive and releasably retain the shank end of the dental point blank.

Adjacent the portion 11 of the back which is the portion to be coated with abrasive grain, but removed therefrom sufficiently to provide a chamber, the inner wall of which is the surface to be coated, I provide porous means 13 forming the outer wall of said chamber and thus serving to compact the abrasive granules with which the chamber is filled and to hold the inner layer of said granules and the back 11 in mutual contact. In the specific illustration given herein, the porous means 13 is in the form of a hollow container, the lower portion 20 of which is preferably shaped to conform to the shape of the article to be coated with abrasive, whereby the combined thickness of the layer of abrasive surrounding the surface of back 11 plus the surrounding wall of container 13 will be uniform thus facilitating an even electro-deposition of plating metal on all portions of back 11 as will be more fully explained. The upper portion 21 of container 13 is substantially cylindrical and is adapted to be received and held by spring fingers 22 of an inverted cup-shaped collet-like member 23, which is secured on shaft 14, preferably integrally therewith, and is adapted to fit within the cup-shaped member 16. The spring fingers 22 may be formed by dividing the annular wall 24 of member 23, as by the vertically extending spaced slots 25. Thus in the specific embodiment of the invention described herein when the shank 10 of a dental point blank is inserted in its holder 12, comprising the lower end of shaft 14, and these members are assembled with container 13, the portion 11 of the dental point blank projects into the hollow interior of the lower portion 20 of said container 13 and there is thus formed an annular chamber 26, the inner wall of which is the frusto-conical surface of said portion 11, and the outer wall of which is the porous wall of container 13. The said annular chamber 26 being of uniform cross section it will be apparent that when abrasive granules 60 are introduced into the said chamber all portions of the surface of portion 11 will be covered to an equal depth with abrasive grains which will be evenly and closely distributed over the surface of portion 11, and the inner layer of said abrasive grains so distributed will be held in physical contact with the surface of portion 11 through the action of the remainder of the mass of abrasive grains and the porous retaining means, constituted by the wall of chamber 13 in the specific embodiment of the invention illustrated herein. It will also be noted that all portions of the surface of portion 11 are substantially equally spaced from the outer surface of the wall of container 13.

Communicating with chamber 26 are the more or less vertically extending passageways 27 which at their upper ends respectively are flared outwardly at 28 to register with passageways 29, extending through the horizontal wall of cup-shaped support member 16, through ports 30 in the horizontally extending portion of the cup-shaped member 23. If desired, to facilitate supplying granules to chamber 26, funnel means 31 may be inserted in the passageways 29, through ports 30, with the lower end of said funnel means

in registry with the outwardly flared upper ends 28 of passageways 27.

At its upper end cup-shaped support member 16 is provided with a laterally extending annular flange 32 by which the assembly comprising support 16, shaft 14 with its cup-shaped holder 23 for container 13, and container 13, may be conveniently suspended in an electro-plating bath chamber, as by resting on the top 33 of a receptacle 34 containing an electro-plating solution 35, the top 33 being bored to permit insertion therethrough of the body of holder 16 and the container assembly.

The porous retaining means, which in the illustrative embodiment of the invention described herein is the container 13, is immersed in the electrolyte 35, preferably to a level slightly above the top of the back to be coated with plating metal as indicated at 36, Figures 1 and 3. Plating metal is supplied from anode means 37, which may be formed of any suitable metal for plating, preferably a soft strong metal such as copper, chromium, or nickel. The anode means preferred for the specific embodiment of the invention described herein consists of a number of anodes 37 also immersed in the electrolyte 35 and equally spaced from one another and from the surface of back 11. This arrangement of the anodes 37 results, in the case of the specific embodiment of the invention illustrated herein, in the disposition of the anode members 37 at evenly spaced intervals around the periphery of a circle concentric with the axis of the frusto-conical back 11, and inclined at an angle corresponding to the taper of the surface of back 11 and the surrounding portion of the wall of container 13. The anodes 37 are attached at their upper ends respectively in any suitable way, by welding, for example, or by solder 38 as illustrated herein, to the posts 39 formed of any suitable metal, preferably brass, which extend through bores in the top 33 and are screw-threadedly engaged as at 41 in collars 40 which rest upon the receptacle top 33. The posts 39 may also be provided with annular flanges 42 adapted to rest against the lower surface of top 33 to prevent upward movement of the posts 39 and to cooperate with collars 40 in securely positioning the posts 39 respectively.

The upper end of holder shaft 14 is bored radially at 43 for connection to electrical conductor 45 leading to the negative pole of a source of electrical energy and has a bore 44, extending vertically from its upper end to the radial bore 43, in which a thumb screw 46 may be adjustably seated to press upon and positively engage the end of the said conductor inserted in bore 43 as indicated in Figure 3. Similarly each of the posts 39 is provided adjacent its upper end with a radial bore 49 for connection to conductor 51 leading to the positive pole of said source of electrical energy and has a bore at 50 extending vertically from its upper end to the radial bore 49 in which a thumb screw 52 may be adjustably seated to press upon and positively engage the said conductor, as indicated in Figure 1.

It will thus be seen that the anodes 37 are connected to the positive end of an electro-plating circuit and the backing 11 to be coated with abrasive granules, which as illustratively disclosed herein is the frusto-conical surface of a dental point blank, is connected through the metal shaft 14 and its holder end 12, with the negative end of an electro-plating circuit, thus constituting cathode means on which the plating metal is deposited from the electrolyte 35 pen-

trating the pervious wall of abrasive retaining member 13 and the mass of granules when the electro-plating circuit is energized.

It will be understood that the arrangement of the anodes 37 in equally spaced relation to the back 11 tends to provide uniform current density in the portion of the electrolyte contacting the porous member 13 and passing through member 13 into contact with back 11, to insure a uniform rate of electro-deposition of the plating metal on all portions of back 11. It will also be readily understood that when the space between the porous retaining member 13 and the back 11 to be coated with abrasive granules is filled with abrasive granules 60 the electrolyte penetrating through the pervious wall of member 13, and through the mass of abrasive granules, will deposit the plating metal on back 11 in the spaces not covered by the abrasive granules in contact with the surface of back 11, thereby building up a thickness of metal gradually encompassing the abrasive granules to a height determined by the character of the electrolyte solution and the period of the plating operation, and thereby forming a matrix positively and firmly embedding the abrasive granules and binding them to the back 11.

While preferably the plating operation will be continued only long enough to bind a single layer of abrasive granules to the surface of back 11 it will be understood that, if desired, the electro-depositing of plating metal may be continued until the accretion on back 11 encompasses a second or further layer of abrasive granules of a mass of abrasive granules interposed between the back 11 and the porous retaining member 13, thereby providing an abrasive coating of any desired depth.

The receptacle 34 and its top 33 may be of any suitable material but is preferably made of Pyrex glass. Preferably the top 33 of receptacle 34 is removable, having pins 53 for readily centering top 33 on receptacle 34, so that the porous retaining member, comprised herein by the container 13, and the anode means 37, together with their respective supporting holders, may be lifted from or immersed in the electrolyte 35 as a unit. Preferably also the top 33 is provided with suitable vents 54 to admit air into, or egress of gases from, receptacle 34.

If desired the shaft 14 may also be radially bored at 47 and have a cross pin 48 inserted in bore 47 to serve as a hand piece to give leverage in screwing or unscrewing the shaft 14 and the cup-shaped holder 16.

The container 13, shown herein as illustrative of porous means for retaining abrasive granules against a backing to be coated with the granules, preferably comprises an inner annular two-part portion 55 divided as for example along line 56 into the halves 55a and 55b, and an outer annular portion 57, concentric with the said inner portion when the parts 55a and 55b are assembled. Outer portion 57 is adapted when inserted in collet-like cup-shaped support member 16 to hold inner annular portion members 55a and 55b firmly around the lower end of shaft 14 and particularly around the shank 10 of the dental point just above the frusto-conical or back portion 11 and against the base thereof, providing a closure to prevent coating of the shank.

Any suitable metal may be used for plating. However, a strong metal which will produce a strong coating is desired. The dental point 10, back portion 11, illustrated herein as the back

to be coated, may be made out of German silver and in such cases the anodes 37 may be nickel. In many cases it is desired to produce a coating of abrasive upon a steel back and in such cases the anode means may be nickel or desirably chromium. The electrolyte 35 will, of course, be selected in accordance with the particular metal being used to plate. For plating with nickel, a nickel sulphate formula may be used. The following formulae may be used:

TABLE I

Warm nickel (Watts type)

Single nickel salt	oz./gal.	25-45
Nickel chloride	oz./gal.	6-9
Boric acid	oz./gal.	4-6
pH Colorimetric		5.2-5.8
Temperature	°F.	120-160
Current density	amp./sq. ft.	15-50

For chromium plating the following solution can be used:

TABLE II

Chromium plating

Chromic acid	oz./gal.	40
Sulfuric acid	oz./gal.	.40
Chromic acid/sulphate ratio		100-75
Temperature	°F.	115-140

Current density amp./sq. ft. 100-600

The electric current density used for nickel plating may suitably be from 25 to 40 amperes per square foot. For chromium plating a higher density, on the order of 100 amperes per square foot, or more, may be used.

In all cases it is desirable to work on the low side of the current density tables. In this way a stronger plating is achieved.

The grit size of the abrasive used may be widely varied according to the body to which the coating is applied and the grinding characteristics desired to be obtained. In the above illustration of the embodiment of the invention, diamond grains having a grit size of 150 mesh may be employed. The thickness of the coating of plated metal deposited is preferably more than one-half, say, from one-half to slightly more than three-quarters of, the radial thickness of the diamond granules from the surface of back 11, and in the specific embodiment of the invention given herein, will be on the order of from two to three thousandths of an inch. For electro-depositing a plating metal to approximately such depth on a back, such as the frusto-conical portion of the dental point selected herein to illustrate a practical application of the invention, the electro-plating operation should be carried on for a period on the order of one and a half hours.

After the coating operation the coated body should be placed in boiling water for a short period to harden the surface and to drive out hydrogen the presence of which might tend to render the coating brittle. The metal diamond point or other abrasive product produced as described above is then dressed, as, for example, with a crystolon stick, and is ready for use.

It will thus be seen that there has been provided by this invention a method, apparatus, and an article in which the various objects hereinabove set forth together with many thoroughly practical advantages are successfully achieved.

As various possible embodiments might be made of the mechanical features of the above invention and as the art herein described might be

varied in various parts, all without departing from the scope of the invention, it is to be understood that all matter hereinbefore set forth or shown in the accompanying drawing is to be interpreted as illustrative and not in a limiting sense.

What I claim is:

1. In combination with, a cup-shaped support-member adapted to be positioned above an electroplating bath, with its open end extending toward the bath, a cathode member extending through the closed end of said cup-shaped support member and having means adjacent its lower end to support a blank, said cathode member having a cup-shaped portion adapted to fit within said cup-shaped support and forming a collet, a porous container, having an outer annular portion adapted to be spring-fitted into said collet and to surround the lower end of said cathode member and the blank supported thereby and to provide a space between said outer portion and said blank, and an inner annular portion divided into a plurality of parts and adapted to provide a shield around the lower end of the cathode member and to be held firmly against said cathode member by the said outer annular portion of said container when the latter is inserted in said collet, and means for introducing granules into said container between the inner and outer annular portions of said container and into said space between said outer portion and said blank.

5 2. Apparatus for making abrasive articles comprising a holder for a metal blank having a depending flange extending concentrically there-around and forming a collet, and a porous receptacle having a portion adapted to be spring fitted into said collet and having a portion adapted to enclose said holder and to provide a space between its wall and a blank positioned therein by said holder, said holder and said receptacle having complementary passageways through which abrasive granules may be introduced into the said porous receptacle and interposed between said blank and the porous wall of said receptacle.

10 15 3. In apparatus for fixing abrasive granules on a backing electrolytically, a porous receptacle adapted to be suspended in an electroplating bath, a cathode member extending into said porous receptacle and having means for supporting a metal blank within said receptacle in spaced relation to the wall of the receptacle, means for introducing abrasive granules into said porous receptacle and around the portion of said blank to which it is desired to affix the abrasive granules, and means supported in said porous receptacle for shielding another portion of said blank from contact with said granules, and from the plating action of an electroplating bath in which said porous receptacle is sus-
20 25 30 pended.

EDWARD VAN DER PYL.
